HAT BOX

David Bennett, Rockville Centre, N.Y., assignor to
The Modern Box Corporation, Brooklyn, N.Y.

Filed June 4, 1973, Ser. No. 366,626

Term of patent 14 years

Int. Cl. D9—03

U.S. Cl. D9—240

FIG. 1

FIG. 2

FIG. 3

FIG. 4

FIG. 5

FIG. 6

FIG. 7

FIG. 1 is an exploded, top perspective view of a hat box showing my new design;

FIG. 2 is a top plan view with the cover removed;

FIG. 3 is a side elevational view, the opposite side being the same in appearance as the side shown;

FIG. 4 is an end elevational view, the opposite end being the same in appearance as the end shown;

FIG. 5 is a sectional view taken substantially along the line 5—5 of FIG. 2;

FIG. 6 is a view similar to FIG. 1 but showing a modified form of my new design;

FIG. 7 is a top plan view thereof.

The bottom of the hat boxes are plain.

I claim:

The ornamental design for a hat box, substantially as shown and described.
